UNITED STATES PATENT OFFICE.

JOHN BRUNNER, OF NAPOLEON, INDIANA.

GRAIN-SEPARATOR.

SPECIFICATION forming part of Letters Patent No. 269,000, dated December 12, 1882.

Application filed May 20, 1882. (No model.)

To all whom it may concern:

Be it known that I, JOHN BRUNNER, a citizen of the United States, and a resident of Napoleon, in the county of Ripley and State of Indiana, have invented a new and valuable Improvement in Grain-Separators; and I do hereby declare that the following is a full, clear, and exact description of the construction and operation of the same, reference being had to the annexed drawings, making a part of this specification, and to the letters and figures of reference marked thereon.

Figure 1 of the drawings is a vertical sectional view of my separator. Fig. 2 is a rear view of the same with the fan-casing and fan removed, and Fig. 3 is a detail perspective view of one of the arms of the fan.

This invention has relation to grain-separators; and it consists in the construction and arrangement of parts, as will be hereinafter fully described, and particularly pointed out in the claims.

In the accompanying drawings, the letter A designates the uprights of the case; B, the side walls, which are of tapering form, being wider toward the front end, where the fan-case D is located.

C indicates the sloping top, which shelves downward and backward to the open end E, where the chaff is blown out.

F represents the bottom guide-board, which shelves downward from the open end E, extending to the edge of the first transverse discharging-chute G, into which it delivers.

H represents the long shoe, which extends from under the hopper K to the open end E of the case, and is suspended to the upper portion thereof by staples and links. It is provided under the hopper with the inclined guide-board L, the slope of which is like that of the top C of the case. This board delivers upon the inner end a of the upper or first coarse screen, S, the slope of which is slightly inward, or from the open end a of the screen forward, as indicated in the drawings. Under the screen S, and parallel thereto, is the second coarse screen, S', the inner end a' of which is situated immediately under the inner end a of the upper screen. The bottom or fine screen, S", has a much steeper inclination or down-

ward slope from the open end of the case forward to its delivery end a", which is situated immediately over the separating partition or walls b, between the transverse delivery-chutes G and G'. The fine screen S" extends a little in front of the upper coarse screens, and receives what passes over the ends thereof, in this manner conveying the larger grain into the second chute, G'. The fine seed and cockle pass through the screens, and are conveyed by the inclined bottom guide, F, into the first transverse chute, G, which lies under the inner end a" of the steep screen S". The transverse chutes G and G' have side walls, b and b', extending up nearly to the level of the lower end of the fine screen, and are formed with sloping bottoms c, which are inclined in opposite directions. These discharging-chutes are located, as indicated, under the middle portion of the case, and extend from side to side thereof, as shown in the drawings. The object is to run all grain and seed toward the middle portion of the case, so that the blast will meet it, whereby an excellent cleaning effect is produced. The dividing wall or walls b between the chutes is arranged immediately and vertically below and near the inner end a" of the fine screen, the slope of which is sufficiently rapid to prevent clogging, and to allow time for the blast to take effect upon the chaff and light stuff which passes through the upper screens. The tapering blast-throat V, between the sloping top C and the inclined bottom guide, F, is designed to produce, when the fan is in operation, a concentration of the wind, so that the light stuff will be blown out in a forcible manner.

The fan-shaft e is rectangular, and is formed with cranks g at the sides within the case, which are connected to the sides of the shoe by the horizontal pitman-rods h. The shaft e is made round where the pitman-cranks surround it, and is provided with a pinion, k, which engages the driving-wheel l.

P represents the fan, which consists of four blades, R, connected by arms m. These arms are formed with lateral notches n, whereby they engage each other, and with smaller rectangular notches, z, for the reception of the fan-shaft e, made in the opposite edges from the

fan-blades, and having their bottoms at right angles, so that when they are adjusted on the squared shaft *e* and the sections are moved together by a sidewise motion they will be locked on the shaft. Fastening-pins are placed in perforations through the shaft to secure the sections in position after adjustment.

Having described this invention, what I claim, and desire to secure by Letters Patent, is—

1. In a grain-separator having the downwardly-inclined top *C* and the oppositely-inclined bottom guide, *F*, the combination therewith of the shoe *H*, having the downwardly-inclined guide-board *L*, extending to the lower

end of the screen *S*, the screens *S*, *S'*, and *S''*, and the transverse inclined discharge-chutes *G* *G'*, substantially as specified.

2. In a grain-separator, the combination of the rectangular fan-shaft *e*, having lateral cranks *g*, pitmen *h*, fan-blades *R*, notched interlocking arms *m* *n* *z*, engaging each other, and the fan-shaft, substantially as specified.

In testimony that I claim the above I have hereunto subscribed my name in the presence of two witnesses.

JOHN BRUNNER.
